UNITED STATES PATENT OFFICE.

LOUIS COX, OF BIRMINGHAM, ENGLAND, ASSIGNOR OF ONE-HALF TO EDWIN JOHN BURT, OF LONDON, ENGLAND.

PAVING BLOCK.

Application filed September 10, 1923. Serial No. 661,920.

To all whom it may concern:

Be it known that I, LOUIS COX, a subject of the King of Great Britain, residing at 42, Clarence Road, Harborne, Birmingham, 5 Warwick, England, have invented new and useful Improvements in Paving Blocks, of which the following is a specification.

This invention relates to paving blocks of the kind in which the wearing surface is 10 in the form of a rubber or like pad attached to blocks composed of wood, concrete, metal or other suitable materials by means of mutually engaging projections, grooves or recesses.

15 It has been proposed in a block of the above described type to provide the rubber face or pad with a series of transverse parallel ribs, lugs or keys of dovetail form, and the block to which it is connected has been 20 formed with corresponding grooves or recesses for their reception and in some cases locking rods have been provided passing through the block and the lugs on the pad as a further means of keeping the pad securely fastened to the block.

25 It has also been proposed to provide a concrete paving block with a pre-moulded rubber wearing surface which is continued down the vertical surfaces of the block and 30 then turned into the concrete in the form of a fin, the underside of the pad also being provided with perforated fins of substantially straight form with rounded ends which fit corresponding recesses in the face 35 of the block.

According to my invention in a paving block of the kind referred to, I form the rubber or like pad with a series of parallel ribs, and the edges of the pad with continuous side and end downward extensions 40 marrying into the vertical sides of the block and integral with the ribs, wires being threaded transversely of the ribs to obtain a keying effect in the block and to reinforce 45 the latter.

In a suitable arrangement for carrying out the invention the downward extension on the pad has its lower edge sloped downwards from the outside and the ribs which 50 are of about the same depth as the said extension have lugs thereon for the recep-

tion of the keying and reinforcing wires which have their ends bent downwards.

The ribs may be provided with longitudinal beads to increase the keying effect. 55

To enable the invention to be fully understood I will describe it by reference to the accompanying drawing, in which;

Figs. 1 and 2 are respectively a longitudinal sectional elevation and a transverse 60 section of a paving block constructed in accordance with the invention.

Figs. 3 and 4 are perspective views showing the improved block provided with a grooved under surface. 65

Fig. 5 is a perspective view showing a mode of laying the said blocks.

a is the block of wood, concrete, metal or other material and *b* is the rubber face or pad applied thereto, *c* indicating the parallel ribs on the underside of the said face and which are moulded into the block *a*. 70

*b*¹ indicates the continuous side and end downward extensions which marry into the vertical sides in the block *a*, with a sloping 75 lower edge as shown. In this arrangement, projecting longitudinal beads may be formed on the ribs *c* to increase the keying effect. *f* indicates the wires threaded transversely through the ribs *c*, *c*¹ indicating lugs on the 80 latter for the purpose.

As indicated in the drawings the upper surface of the face *b* may be studded, grooved or otherwise moulded in any suitable design to produce studs, grooves, or 85 projections to prevent side-slip or skidding, and so that pedestrians or horses may obtain a firm hold or grip.

Fig. 3 shows a block having a rubber face or pad on the upper face of which projecting ribs are formed at an inclination to the sides of the block and Fig. 5 shows the blocks laid in position on a road bed in rows, the alternate rows having the said ribs at different inclinations. 90 95

These blocks are preferably bedded on a layer of felt or other suitable material *g* and are grooved or serrated as at *h* as indicated in Fig. 4.

As roads or the like paved with the improved blocks will be noiseless and dustless, and require no watering, they will be very 100

suitable for putting down outside places of worship, hospitals, schools and other public buildings.

What I claim and desire to secure by Letters Patent is:—

A paving block comprising a block of rigid material, having an inwardly and downwardly inclined rabbet extending around the upper edges thereof, said block

having transverse grooves adjoining said rabbet, a resilient pad having a downwardly projecting border flange extending into said rabbet, depending transverse projections on the pad engaging said transverse grooves and a wire moulded in said block for holding said resilient pad in place.

LOUIS COX.
